UNITED STATES PATENT OFFICE.

PETER H. HENDRICKSON, OF COEUR D'ALENE, IDAHO.

STARTER FOR AUTOMOBILES.

1,404,121.

Specification of Letters Patent. Patented Jan. 17, 1922.

Application filed May 9, 1921. Serial No. 467,962.

To all whom it may concern:

Be it known that I, PETER H. HENDRICKSON, a citizen of the United States, residing at Coeur D'Alene, in the county of Kootenai and State of Idaho, have invented a new and useful Starter for Automobiles, of which the following is a specification.

This invention relates to starting devices used in connection with motor vehicle engines, for imparting the initial movement to the engine.

The primary object of the invention is to provide a mechanical starting device to be applied adjacent the forward end of an engine block, there being provided novel means for connecting and disconnecting the starting device by the manipulation of a foot lever disposed in easy access to the operator.

A still further object of the invention is to provide a starting device of this character which may be moved to a position remote from the steering wheel of the vehicle, when the same is not in use, and one which may be readily and easily moved to its operative position when it is desired to start the engine.

Another object of the invention is to provide a starting device which may be manipulated from the operator's seat of a motor vehicle, thereby eliminating the necessity of the operator alighting from the car to accomplish the starting of the invention.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to drawings:

Figure 1 is a side elevational view of the invention, showing the same as applied to an internal combustion engine, the gear casing housing the starting gears, being shown in section.

Figure 2 is a sectional view taken on line 2-2 of Figure 1.

Figure 3 is a sectional view taken on line 3-3 of Figure 1.

Figure 4 is an elevational view of the

starting device, showing the cover of the gear casing as removed.

Figure 5 is a sectional view taken on line 5-5 of Figure 1.

Referring to the drawings in detail, the reference character 5 designates an internal combustion engine to which the invention is applied, the dash board of the motor vehicle supporting the engine being indicated at 6, and the steering column, which forms a support for one of the elements of the invention being indicated at 7.

The starting device includes a gear casing indicated generally by the reference character 8 and comprises an upper section 9 and a lower section 10, the sections being provided with lateral flanges provided with openings to accommodate the securing bolts 11 by means of which the sections of the casing 75 may be secured together. Each section is provided with suitable bearings indicated at 12 and 13 respectively, the bearing 13 accommodating the movable shaft 14 that carries a clutch member 15 on one end thereof, and as shown one end of the shaft 14 operates in an elongated opening 16 formed in the opposite wall of the casing, the opening being of a length to permit reciprocation of the shaft 14, to move the same into 85 and out of operation.

Mounted on the shaft 14 is the main pinion 17 which is keyed to the shaft 14 so that movement of the pinion will result in a relative rotary movement of the shaft 14 to 90 operate the clutch member 15.

A collar 18 is formed with the pinion 17 and is provided with a groove 19 to accommodate the inwardly extending lugs 20 formed on the yoke 21 which is bolted to the shaft 22 that is supported within the lower section of the casing, the ends thereof being disposed in the bearings 23 to permit the shaft 22 to rock within the casing, to accomplish the movement of the shaft 14.

Secured to the shaft 22, is an arm 24 which has its upper end pivotally connected to the rod 25, which rod has pivotal connection with the foot lever 26, as at 27, the connection between the rod 25 and foot lever being 105 such that when the foot lever is forced downwardly, the rod 25 is moved rearwardly to the end that the clutch member 15 is moved into cooperative relation with the clutch member 28 that is carried on the forward 110 end of the engine drive shaft. Positioned on the rod 25, and disposed between the

knuckle 29 that has connection with the arm 24, and one of the walls of the casing, is a coiled spring 30 which normally moves the rod to a position to cause the clutch members 5 15 and 28 to be disengaged.

Meshing with the pinion 17 is a pinion 31 which is carried at one end of the shaft 32 that has connection with the operating rod 33, as through the medium of the universal 10 joint 34, which rod is of a length to extend to a position adjacent to the steering column 7, where the same is provided with a laterally extending lug 35, which lug 35 moves in the slot 36 formed in the tubular 15 member 37 which is supported in the bracket members 38 and 39 respectively, the tubular member being designed to move through the bracket members 38 and 39, to accomplish the operation of the device.

20 The upper end of the member 37 is provided with teeth 40 which cooperate with the teeth formed on the head 41, so that movement of the head in one direction will produce a relative movement of the tubular 25 member 37 and shaft 33, but permit of movement of the shaft 33 and tubular member 37 in the opposite direction, independently of the head 41. A laterally extending ear 42 forms a part of the head, and this ear provides a support for the operating handle 43, which is provided with an elongated opening to accommodate the bolt 44, which is carried by the ear, the connection between the head and handle 43 being such as to permit the 30 handle to be moved to a vertical position allowing the tubular member 37 to be moved to a position as indicated in dotted lines in Figure 1 of the drawings, whereupon the operating device is out of the way of a person controlling the motor vehicle.

In the use of the device, assuming that it is desired to start the engine equipped with the invention, it is only necessary to move the tubular member 37 from a position as indicated in dotted lines in Figure 1 of the drawings, to the position as indicated in full lines, whereupon movement of the foot lever 26 rocks the shaft 22 and moves the 45

clutch member 15 into engagement with the clutch member 28 of the engine drive shaft. 50 With the elements in this position, it will be seen that upon the rotation of the hand lever 33, rotary movement is imparted to the pinion 31, which in turn imparts rotary movement to the pinion 17 and shaft 14 to give 55 the engine the initial movement to start the same.

When the engine has been started, the foot lever 26 is moved to its normal position by means of the coiled spring 30 and the handle 60 43 and tubular member 37 are moved to positions as indicated in dotted lines in Figure 1 of the drawings.

Having thus described the invention, what is claimed as new is:—

1. In combination with the drive shaft of an internal combustion engine, a starting device comprising a casing, gearing in the casing, means for imparting rotary movement of the gearing to the drive shaft, said means comprising a rod, a tubular member disposed on the rod, means for connecting the tubular member and rod, a head supported at one end of the tubular member, an operating handle adjustably connected with the head, and said head adapted to be clutched with one end of the tubular member.

2. In combination with the drive shaft of an internal combustion engine, a starting device including a casing, gearing within the 80 casing, means for imparting rotary movement of the gearing to the drive shaft, means for imparting rotary movement to the gearing, said means including a rod, a tubular member adjustable longitudinally of the rod, 85 and an adjustable operating handle having connection with one end of the tubular member.

In testimony that I claim the foregoing as my own, I have hereto affixed my signature 90 in the presence of two witnesses.

PETER H. HENDRICKSON.

Witnesses:

T. A. BALL,
JOE PETERSEN.
